HENRY JOSEPH ROUND, OF LONDON, ENGLAND, ASSIGNOR TO RADIO CORPORATION
OF AMERICA, A CORPORATION OF DELAWARE

THERMIONIC AMPLIFIER AND CIRCUIT ARRANGEMENT THEREFOR

Application filed February 18, 1928, Serial No. 255,218, and in Great Britain February 23, 1927.

This invention relates to thermionic amplifiers, and circuit arrangements therefor, and more particularly to thermionic audio frequency amplifiers of the so-called resistance coupled type, i. e. amplifiers in which the varying voltage drop occurring across a resistance or resistive impedance (hereinafter termed the anode resistance) in the anode circuit of one valve is transferred to the input side of the next.

In one well known form (generally termed resistance capacity coupling) of resistance coupled amplifier, the anode of the first valve is connected to the anode battery through an anode resistance and to the grid of the next valve through a coupling condenser. The grid of the said second valve is connected to the cathode through another resistance (generally known as a grid leak) a grid bias battery being interposed, if desired.

In cases in which the first valve is employed as a detector or rectifier, it is usual to shunt the anode resistance by a condenser which acts as a high frequency by-pass.

In resistance coupled amplifiers, particularly those used in broadcasting receivers, the use of high magnification valves and anode resistances of high value results in a strong tendency for the amplification to fall off over the higher frequencies, particularly those above 2,000 cycles per second, due very largely to the capacities of the valves themselves.

Moreover, when a by-pass condenser is employed in shunt with an anode resistance, this condenser also tends to reduce amplification over the higher frequencies.

The principal object of the present invention is to eliminate or minimize to a desired degree the effects set forth hereinbefore.

According to this invention an inductive reactance is inserted in the lead from the output electrode of one valve to the input electrode of the next.

The inductive reactance should be of a comparatively large value and may be suitably formed as an iron-cored choke and, in the case of a resistance-capacity coupled amplifier, may be inserted between the coupling condenser and the "anode end" of the anode

resistance of the first valve or between the coupling condenser and the "grid end" of the grid leak or between the "grid end" of the grid leak and the grid of the next valve. In some cases it may be found desirable to provide such inductive reactances connected in more than one of these positions, though generally one choke only will be found sufficient.

The inductive reactance is preferably so constructed and arranged that its insertion results in the addition of only a small amount of capacity between the "anode end" of the anode resistance of the first valve and the grid of the next valve.

If desired, a condenser may be inserted between the grid of the succeeding valve and the cathode thereof, and further, the grid leak may be employed as a damping resistance or an additional resistance may be inserted between the grid and the cathode.

It will be seen that the addition of the inductive reactance in combination with the valve grid capacity and any additional condenser forms a resonant circuit giving an increase of voltage across the grid and cathode, thereby tending to neutralize any previous drop of amplification. The grid leak or an additional resistance may be used to adjust the amount of this resonance; a comparatively sharp cut-off follows the resonant point, which cut-off can, for example, be adjusted to 5000 or 6000 cycles per second, thereby cutting out undesirable high note sounds.

The inductive reactance has the additional advantage that it serves as a block to prevent high frequency currents passing into the audio frequency amplifier, and thereby minimizes undesirable reaction effects, and the imposition of damping upon any tuned circuit which may be associated with the input circuit of the valve in whose anode circuit the said reactance is connected.

The invention is illustrated in the accompanying diagrammatic drawings, which show in conventional circuit representation, three modifications of the said invention.

Referring to Figure 1, 1 is a thermionic valve comprising a cathode 2, grid 3, and anode 4, the last mentioned electrode being connected through an anode resistance 5 and

an anode battery 6 to the cathode. The anode 4 is connected through a coupling condenser 7 and an iron-cored choke 8 to the grid 9 of a second thermionic valve 10. The junction point of the condenser 7 and the choke 8 is connected through a grid leak resistance 11 and bias battery 12 to the common cathode connection which is also connected through a condenser 13 which is shunted by a damping resistance 14 to the grid 9. 15 is a condenser shunting the resistance 5 and battery 6.

In the modifications shown in Figures 2 and 3, like parts are indicated by like reference numerals. The said modifications differ from that shown in Figure 1 by the omission of the damping resistance 14 in Fig. 2, and the different location of the choke 8 in Fig. 3.

Having now particularly described and ascertained the nature of my said invention and in what manner the same is to be performed, what I claim is:

1. In an impedance coupled thermionic amplifier, adapted to operate over a predetermined frequency range and normally producing greater amplification at one end of the range than the other end, the combination with an inductive reactance connected between the anode of one thermionic valve and the grid of the succeeding thermionic valve, of a condenser directly connected between the grid of the succeeding valve and the cathode thereof, said condenser being independent of the said succeeding valve, said condenser and reactance being designed to provide a network resonant to a frequency at said other end to neutralize drop of amplification at the latter end.

2. In a resistance coupled thermionic amplifier, adapted to operate over a predetermined frequency range and normally producing greater amplification at one end of the range than the other end, the combination with an inductive reactance connected between the anode of one thermionic valve and the grid of the succeeding thermionic valve, of a condenser directly connected between the grid of the succeeding valve and the cathode thereof, said condenser being independent of the said succeeding valve, said condenser and reactance being designed to provide a network resonant to a frequency at said other end to neutralize drop of amplification at the latter end, and a damping resistance shunting said condenser.

3. An amplifier comprising a plurality of resistively coupled thermionic valves, an inductive reactance between the anode of a valve and the grid of a succeeding valve, and a capacitive reactance connected between the grid and cathode of said succeeding valve, said latter reactance combining with the inductive reactance to form a resonant circuit across the input terminals of said succeeding valve to produce an increase of voltage

across the grid and cathode of said succeeding valve at high frequencies, whereby a decrease in amplification at high frequencies is eliminated.

4. An amplifier comprising a plurality of resistively coupled thermionic valves, an inductive reactance comprising a choke coil between the anode of a valve and a grid of a succeeding valve, and a capacitive reactance connected directly between the grid and cathode of the succeeding valve, said capacitive reactance together with the grid cathode capacity of the succeeding valve combining with the choke coil inductance to form a resonant circuit across the input terminals of said succeeding valve, and a damping resistance associated with said capacitive reactance to vary the amount of resonance in said resonant circuit.

5. In an amplifier, the combination with a plurality of resistance-coupled thermionic vacuum tubes having a resistance in the anode circuit of the first tube, a grid leak resistance in the input circuit to the second tube, and a coupling condenser in the said anode circuit, of an inductive reactance connected in series with said coupling condenser, and a second condenser directly connected in shunt to the input circuit of the second tube, said condenser being so related to said inductive reactance as to form an input resonant circuit whereby a decrease in amplification at relatively high frequencies is compensated for.

6. The combination in an amplifying system of resistance-coupled vacuum tube amplifiers in which the amplification at the relatively high frequencies tends to fall off, said amplifiers having a resistance in the anode circuit of the first tube, a grid leak resistance in the input circuit to the second tube, and a coupling condenser in the said anode circuit, an inductive reactance connected in series with said coupling condenser and a second condenser directly connected in shunt to the input circuit of the second tube, said second named condenser together with the grid-cathode capacity of the second tube combining with said inductive reactance to form an input resonant circuit whereby the decrease in amplification at the relatively high frequencies is compensated for.

7. In an impedance coupled thermionic amplifier, adapted to operate over a predetermined frequency range and normally producing greater amplification at one end of the range than the other end, the combination with an inductive reactance connected between the anode of one thermionic valve and the grid of the succeeding thermionic valve, of a condenser directly connected between the grid of the succeeding valve and the cathode thereof, said condenser being independent of the said succeeding valve, said condenser and reactance being designed

to provide a network resonant to a frequency at said other end to neutralize drop of amplification at the latter end and a high frequency by-pass condenser connected between the anode and cathode of said first valve.

5 8. In an impedance coupled thermionic amplifier, adapted to operate over a predetermined frequency range and normally producing greater amplification at one end of the 10 range than the other end, the combination with an inductive reactance connected between the anode of one thermionic valve and the grid of the succeeding thermionic valve, of a condenser directly connected between the 15 grid of the succeeding valve and the cathode thereof, said condenser being independent of the said succeeding valve, said condenser and reactance being designed to provide a network resonant to a frequency at said other 20 end to neutralize drop of amplification at the latter end, said inductive reactance comprising an iron-cored choke.

9. In an impedance coupled thermionic amplifier, adapted to operate over a predetermined frequency range and normally producing greater amplification at one end of the 25 range than the other end, the combination with an inductive reactance connected between the anode of one thermionic valve and the grid of the succeeding thermionic valve, of a condenser directly connected between the grid of the succeeding valve and the cathode thereof, said condenser being independent of the said succeeding valve, said condenser and 30 reactance being designed to provide a network resonant to a frequency at said other end to neutralize drop of amplification at the latter end, a path between the anode and cathode of the first valve including a source 35 of current and a resistor, and a path between the grid and cathode of the succeeding valve including a bias source and a resistor.

10. In an impedance coupled thermionic amplifier, adapted to operate over a predetermined frequency range and normally producing greater amplification at one end of the 40 range than the other end, the combination with an inductive reactance connected between the anode and one thermionic valve 45 and the grid of the succeeding thermionic valve, of a condenser directly connected between the grid of the succeeding valve and the cathode thereof, said condenser being independent of the said succeeding valve, said condenser and reactance being designed to provide a network resonant to a frequency at 50 said other end to neutralize drop of amplification at the latter end, and a condenser connected in series between the reactance and the anode of the first valve.

11. In an impedance coupled thermionic amplifier, adapted to operate over a predetermined frequency range and normally producing greater amplification at one end of the 55 range than the other end, the combina-

tion with an inductive reactance connected between the anode of one thermionic valve and the grid of the succeeding thermionic valve, of a condenser directly connected between the grid of the succeeding valve and the cathode thereof, said condenser being independent of the said succeeding valve, said condenser and reactance being designed to provide a network resonant to a frequency at 60 said other end to neutralize drop of amplification at the latter end, the connection between the reactance and the grid of the succeeding valve including a condenser.

12. In an impedance coupled thermionic amplifier, adapted to operate over a predetermined frequency range and normally producing greater amplification at the low frequency end of the range than the high frequency end, the combination with an inductive reactance connected between the anode 65 of one thermionic valve and the grid of the succeeding thermionic valve, of a condenser directly connected between the grid of the succeeding valve and the cathode thereof, said condenser being independent of the said succeeding valve, said condenser and reactance being designed to provide a network resonant to a frequency at 70 said high frequency end to neutralize drop of amplification at the latter end.

13. In an impedance coupled thermionic amplifier, adapted to operate over a predetermined frequency range and normally producing greater amplification at one end of the range than the other end, the combination with an inductive reactance connected between the anode of one thermionic valve and the grid of the succeeding thermionic valve, of a condenser directly connected between the grid of the succeeding valve and the cathode thereof, said condenser being independent of the said succeeding valve, said condenser and reactance being designed to provide a network resonant to a frequency at 75 80 85 90 95 100 105 110 115 120 125 130

HENRY JOSEPH ROUND.
